UNITED STATES PATENT OFFICE.

LUGI VIEZZI, OF NORTH BERGEN, NEW JERSEY, ASSIGNOR OF ONE-HALF TO JOSEPH STILZ, OF WEST NEW YORK, NEW JERSEY.

WRENCH.

Application filed February 26, 1927. Serial No. 171,263.

My invention relates to a wrench which may have the form of a monkey wrench as well as a pipe wrench.

The general object of my invention is to provide a novel means for giving the movable jaw of the wrench characteristic adjustments for quickly giving the movable jaw in approximate adjustment to the work and also for disposing the controlling means of the movable jaw that said jaw may slip over the angles of a nut in effecting successive grips on the nut.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a view partly in side elevation and partly in section, the plane of the section being indicated by the line 1—1 in Figure 2.

Figure 2 is a longitudinal section on the line 2—2 of Figure 1.

Figures 3, 4, 5 and 6 are transverse sections taken respectively in planes indicated by the lines 3—3, 4—4, 5—5 and 6—6 in Figure 1.

Figure 7 is a side elevation of the wrench with a portion of the handle broken away to show the controlling means for the movable jaw; a comparison of the full line and dotted line positions of the wrench being helpful to an understanding of the mode of manipulating the wrench in successively gripping the nut on different faces in turning the nut.

Figure 8 is a side elevation with part of the handle broken away showing the control means for the movable jaw in position for sliding the movable jaw toward or from the fixed jaw.

In the illustrated example of my invention the numeral 10 indicates the shank of the wrench having a fixed jaw 11 projecting on opposite sides of the shank. Said shank has a handle designated generally by the numeral 12 which in the form shown advantageously comprises spaced side plates 13 having a wooden covering 14 applied thereto. By thus constructing the handle, it is formed with a longitudinal channel in one side. The movable jaw 15 is slidable on the shank 10 toward and from the fixed jaw 11.

A rack 16 is pivoted to the movable jaw 15 as at 17 and has a knob or other suitable

handle member 116 for swinging said rack 16 laterally against the tension of the spring 18, which spring normally maintains the rack in engagement with the block 19 fixed upon a swingable operating element 20 having opposite flanges 21 at the outer edge thereof. The element 20 controls the position and operation of the movable jaw 15 through the medium of the rack 16 and the toothed block 19.

The said element 20 is fulcrumed at 22 between the plates 13, said plates and their wooden coverings 14 being united by transverse rivets 23, the arrangement being such that the element 20 may be swung on its fulcrum 22 so that in the swinging of the element 20 it will cause the block 19 to move rack 16 and jaw 15, it being observed that said block 19 has its teeth in a curved line as best shown in Figure 8. The element 20 normally lies in the channel of the handle.

The wrench as shown in Figures 1 and 7 is employed for turning a nut A. An approximate adjustment of the movable jaw 15 to the nut A is obtained by laterally swinging the rack 16 on its pivot 17 by taking hold of the handle member 116 to completely disengage said rack from the block 19 as in Figure 8, thus permitting the movable jaw 15 to be slid toward or from fixed jaw 11. With the movable jaw in approximate adjustment to the nut A the restoring of the element 20 to the inner position and the swinging of said element 20 on its pivot 22 after the rack 16 has been restored to engagement with the block 19 will cause a movement of the movable jaw into close adjustment with the nut.

Referring to Figure 7 it will be seen that in both the full and dotted line positions the rack 16 is in engagement with the teeth of block 19 and that in the full line position of the parts shown, the element 20 is swung outwardly. In the dotted line position of the parts in Figure 7 the element 20 has been restored to the inner position. When the nut A has been gripped and given one turn, if the element 20 be swung outwardly, the engagement of the block 19 with the rack 16 is yieldable by reason of spring 18 and such that the wrench may be turned from the dotted line position of the jaws to the full line position, the movable jaw at this time slipping over the angles of the nut and the rack 16 will accommodate itself to the yielding of the movable

jaw by the yielding of the spring 18. Hence the movable jaw automatically conforms itself to the movements of the wrench in shifting from one gripping position of the wrench on the nut to the next successive gripping position.

I would state furthermore that while the illustrated example constitutes a practical embodiment of my invention, I do not limit myself strictly to the exact details herein illustrated, since, manifestly, the same can be considerably varied without departure from the spirit of the invention, as defined in the appended claims.

15. What I claim is:

1. A wrench, comprising a shank having a fixed jaw at one end and a channelled handle at its other end, the channel extending longitudinally of the handle a slidable jaw 20 on the shank, a pivoted and spring pressed rack carried by the slidable jaw and extending into the channel of the handle, a member pivoted to the handle of a length to extend approximately to the end of the handle, and 25 normally lying in the channel thereof, and a toothed block secured to the said member and engaging the rack, the teeth of the block being on a curved line.

2. A wrench comprising a shank having a 30 fixed jaw at one end and a handle at the other, the handle projecting laterally of the

shank and having a longitudinal channel, a slidable jaw on the shank, a pivoted and spring pressed rack mounted on the slidable jaw and extending into the channel of the 35 handle, a member pivoted to the laterally projecting portion of the handle and normally lying in the channel of the handle, said member having oppositely projecting flanges overlying the channel of the handle 40 when said member is in said channel, and a toothed block secured to the side of said member opposite its pivot and engaging the rack, the teeth of the block being on a curved line. 45

3. A wrench comprising a shank having a fixed jaw at one end and a handle at the other end, the handle having a lateral projection intermediate of its ends and a longitudinal channel, a slidable jaw on the shank, 50 a member having an enlarged end pivoted to the projection of the handle, said member normally lying in the channel to be grasped by the hand grasping the handle, a toothed block carried by the said member opposite its pivot, and a pivoted and spring pressed rack on the movable jaw and extending into the channel of the handle, said rack being provided with a handle for swinging it 55 against the action of its spring and out of engagement with the toothed block. 60

LUIGI VIEZZI.
